UNITED STATES PATENT OFFICE.

HARRY Y. NORWOOD, OF ROCHESTER, NEW YORK.

ELECTRIC SINGEING INSTRUMENT.

1,020,439.

Specification of Letters Patent. Patented Mar. 19, 1912.

Application filed April 19, 1911. Serial No. 821,992.

To all whom it may concern:

Be it known that I, HARRY Y. NORWOOD, of Rochester, in the county of Monroe and State of New York, have invented certain new and useful Improvements in Electric Singeing Instruments; and I do hereby declare the following to be a full, clear, and exact description of the same, reference being had to the accompanying drawings, forming a part of this specification, and to the reference-numerals marked thereon.

The present invention relates to electrically heated instruments, and it has for its particular object to provide a device of simple construction and capable of ready manipulation, the instrument being especially designed for use where a comparatively high degree of heat is to be attained for singeing hair and similar purposes.

To these and other ends the invention consists in certain improvements and combinations of parts all as will be hereinafter more fully described, the novel features being pointed out in the claims at the end of the specification.

In the drawings; Figure 1 is a view in elevation of an instrument, connected for operation, and constructed in accordance with one embodiment of the invention; Fig. 2 is a view in elevation, showing the instrument in process of construction, and Fig. 3 is a longitudinal central section of the completed device.

Similar reference numerals throughout the several figures indicate the same parts.

The invention, as illustrated in the present embodiment, includes the body portion 1, which is preferably constructed of a refractory insulating material, such, for example, as fire clay, and is provided with a longitudinally extending central bore 2. The resistance element, as embodied in the present form of the invention, is designated at 3, and comprises a wire which extends through the longitudinal bore 2 of the body portion, and is connected at one end to the contact 4, the opposite end of the resistance wire being extended beyond the end and around the outer surface of the body portion, to form the coil 5. The sleeve 6 is secured around one end of the body portion, and is connected with the resistance wire by means of a conductor 7, here shown as a flat strip 7 extending longitudinally of the body portion and fitting closely against the surface thereof. The resistance

coil 5 is first wound about the body portion, as shown in Fig. 2, the conductor 7 being suitably connected to the respective parts, and thereafter there is applied around the resistance coil and the adjacent end of the body portion, a cementitious material 8, preferably fireproof and capable of withstanding a very high temperature without cracking or separating. The cementitious covering serves to entirely inclose the resistance wire and the end of the body portion about which the wire is coiled, and holds the latter rigidly in its proper relation to the body portion and to the contacting strip 7, while affording at the same time, a comparatively large heat retaining surface to be applied to the hair, or other body to be heated or burned. The sleeve 6 is preferably threaded, the end of the body portion being correspondingly threaded to receive the sleeve, which latter constitutes a plug to enable attaching the instrument to a suitable socket, a circuit being completed through the contacts 4 and 6.

In using the instrument, when current is applied, the resistance wire becomes highly heated throughout, both interiorly and exteriorly of the body portion 1, and the cement covering is thus raised to the required temperature for singeing hair, or such other purposes as may be desired.

The instrument is always ready to be instantly connected to an electric circuit, and the parts are heated sufficiently for operation in a very few moments. The contact carrying end of the body portion furnishes a convenient handle by which the device may be held while in use.

I claim as my invention:

1. An electric instrument comprising a body portion of refractory material having a handle, a resistance element surrounding a part of the body portion and having one end inclosed by the body portion, a conductor connected to the opposite end of the resistance element, contacts connected respectively to the conductor and to the first mentioned end of the resistance element, and a cementitious covering surrounding a portion of the resistance element, and forming the exterior of the instrument.

2. An electric instrument comprising a hollow body portion of refractory material having a handle, a resistance element extending through the hollow body portion and surrounding a part of the body portion,

- contacts connected to the ends of the resistance element and a cementitious covering surrounding a portion of the resistance element, and forming the exterior of the instrument.
3. An electric instrument comprising a hollow body portion of refractory material having a handle a resistance element extending through the hollow body portion and surrounding a part of the body portion, a conductor connected to one end of the resistance element, contacts connected respectively to the conductor and to the opposite end of the resistance element, and a cementitious covering surrounding a portion of the resistance element, and forming the exterior of the instrument.
4. An electric instrument comprising a hollow body portion of refractory material having a handle, a resistance element extending through the hollow body portion and extended around the outside of a part of the body portion, a flat conducting strip connected to one end of the resistance element and extending longitudinally of the body portion, a contact sleeve secured to one end of the body portion, and connected to the conducting strip, a contact connected to the opposite end of the resistance element, and a cementitious covering surrounding a portion of the resistance element and the adjacent end of the body portion, and forming the exterior of the instrument.

HARRY Y. NORWOOD.
